PICTURE FRAME

Joseph T. Weinzierl, New Kensington, Pa., assignor to Kensington, Incorporated, New Kensington, Pa., a corporation of Pennsylvania

Application April 25, 1936, Serial No. 76,401

8 Claims. (Cl. 40—152)

This invention relates to picture frames, and particularly to metal frames of the portable type.

An object of the invention is to provide a frame which is of simple construction and one which may be easily and quickly assembled without the use of special tools.

Another object is to provide a frame having corner brackets which, upon assembly, provide an extremely rigid and compact unit.

10 A further object is to provide a frame in which the unifying means are effectively concealed from both front and back and which prevent separation.

Other objects and advantages will be apparent 15 during the course of the following description.

In the accompanying drawing, Fig. 1 is a front elevational view of the improved frame;

Fig. 2 is a side view taken on line II—II of Fig. 1;

20 Fig. 3 is a detail view of a corner of the completely assembled frame showing one form of bracket in place;

Fig. 4 is a detail sectional view taken on line IV—IV of Fig. 3;

25 Fig. 5 is a front elevational view of one form of corner bracket, as shown in Fig. 3;

Fig. 6 is a detail view of a corner of another frame showing another form of bracket in place;

Fig. 7 is a detail sectional view taken on line 30 VII—VII of Fig. 6;

Fig. 8 is a front elevational view of the form of bracket shown in Fig. 6.

In the frame illustrated in Fig. 1, the top and bottom members 1 and the side members 2 are 35 formed from metal, and preferably from a ductile metal such, for example, as aluminum, which has been extruded into shapes of a general character, exemplified by Fig. 2.

In the back of the frame, there is a channel 3 40 coextensive with the top and two sides. This channel receives the glass, picture, filler and easel back, and is formed by the members 4, 5, 6 and 7, as is clearly shown in Fig. 2. The bottom member of the frame, however, varies slightly in 45 form from the top and sides, in that member 4 of the bottom is narrower than it is in the top and sides, and member 5 is omitted entirely. This provides easy access for insertion of those parts commonly employed in retaining a picture 50 in its frame.

Adjacent recess 3 and extending entirely around the frame, there is a pocket formed by the members 6 and 7 and the frame front 8 for the reception of four corner brackets 9. These 55 brackets, as shown in Figs. 5 and 8, are formed

by stamping, and consist of the legs 10 which are at right angles to one another. In both forms of brackets there are provided notches for reception of a small detent or tongue of member 7. Referring to Fig. 5, the notches 11, which take the shape of a trapezoid, are so formed that the side 12 is inclined at an angle of about 45° to the axis of the leg. The depth of the notch is from about one-fourth to one-third the width of the leg 10. This form of corner bracket is used in narrow frames, while the bracket shown in Fig. 8 is employed in wider frames. In the bracket of the wide type there is only one notch, and this is generally of circular form, as shown by reference character 13.

To assemble the frame, one leg 10 of each of the four corner brackets is inserted into the bracket-receiving grooves of the two frame sides. The other legs of the brackets are inserted into like grooves of the top and bottom, and the four sections pushed together as tightly as possible. At this point, the metal immediately over the notches of the corner brackets is depressed or forced into the notches 11 and 13 as by placing a tool on the metal and striking it a sharp blow, 25 as is clearly shown by reference character 14 of Fig. 4 and reference character 15 of Fig. 7. The forces acting on the corners of the frame members serve to draw them closely and firmly together, forming an exceedingly rigid joint at the 30 miter.

The assembled unit may then be given an oxide finish. The electrolyte employed finds its way into the corner joints and in its oxidizing action further serves to make a tighter joint.

I claim:

1. In a picture frame having a plurality of extruded ductile metal sections of channel form, a right-angled corner bracket comprising two legs, each leg having a notch therein for the reception of a portion of the wall of said sections whereby said sections are unitarily joined.

2. In a picture frame having a plurality of extruded ductile metal sections of channel form, right-angled corner brackets having notches in the legs thereof for the reception of a portion of the wall of said sections, one side of each of said notches being inclined at an angle to the axis of the other leg of said bracket.

3. In a picture frame having a plurality of extruded ductile metal sections of channel form, a right-angled corner bracket having notches in the legs thereof for the reception of a portion of the wall of said sections, one side of each of said

notches being inclined at an angle of 45° with respect to the remaining sides.

4. A picture frame comprising a plurality of extruded ductile metal sections of channel form, said sections having a groove therein for receiving corner brackets, notches within said brackets into which a portion of the wall of said sections is forced whereby the forcing of said portions into said notches produces a force acting on said sections to unitarily join the latter.
5. In a picture frame having a plurality of extruded ductile metal sections of channel form, trapezoidal notched corner brackets for the reception of detents formed from the wall of said sections.
6. In a picture frame having a plurality of extruded ductile sections of channel form, a bracket-retaining groove within said sections, corner brackets having a notch of circular form

intermediate the ends of said brackets for the reception of detents formed from the wall of said sections.

7. In a picture frame having a plurality of ductile metal sections of channel form, a right-angle corner bracket comprising two legs, each leg having a notch therein for the reception of a portion of the wall of said sections whereby said sections are unitarily joined.

8. A picture frame comprising a plurality of 10 ductile metal sections of channel form, said sections having a groove therein for receiving a corner bracket, a notch within said bracket into which a portion of the wall of said sections is forced whereby the forcing of said portion into 15 said notch produces a force acting on said sections to unitarily join the latter.

JOSEPH T. WEINZIERL.
